UNITED STATES PATENT OFFICE.

PAUL HEIDTKAMP, OF SCHILDOW, NEAR BERLIN, AND PETER MÜLLER, OF BERLIN-ROSENTHAL, GERMANY, ASSIGNORS TO THE FIRM E. HESSE G. M. B. H., OF BERLIN-ROSENTHAL, GERMANY.

TRAMWAY-SWITCH CONSTRUCTION.

Application filed February 4, 1927, Serial No. 165,957, and in Germany February 6, 1926.

This invention relates to a tramway switch construction with a resilient tongue that is to say to a switch construction which can be adjusted to both its working positions by merely relying to the resiliency of its tongue.

One of the objects of the invention is to improve the connection of the tongue with the body part or skeleton of the switch construction particularly with a view to allow removal of the tongue from the body part or skeleton without opening the pavement.

A further object consists in an improved resilient tongue construction.

Two embodiments of the new switch construction are illustrated in Figures 1-5 and 6-8 respectively.

Figure 1 is a top plan view of the first embodiment and Figures 2 to 5 are cross sections along the lines II-II, III-III, IV-IV, V-V respectively; Figure 5 showing a fragment of the section only.

Figure 6 is a top plan view of the second embodiment and Figures 7 and 8 are sections along the lines VII-VII, and VIII-VIII respectively.

The section along line III-III of Figure 6 is identical with the section along line III-III of Figure 1 and is illustrated in Figure 3.

Figure 9 is a top plan view of an improved resilient switch tongue and Figure 10 a cross section along the line X-X.

In all the figures the resilient switch tongue is designated with the reference letter *a*; *b* designates a supplemental rail body forming an element of the body part or skeleton of the switch which is bolted together with the tongue *a* by bolts *d* and with the rail *e* of the branching track by bolts *s*; *h* is the tongue floor of the switch body; *o* is the usual tongue shaped cover plate closing the angular space between the continuous track and the branch track.

Referring now more particularly to Figures 1-5 it is to be noted that the resilient tongue in this embodiment is laterally serrated; the serration at the side adjacent the supplemental rail *b* engaging a coordinated serration therein as clearly illustrated in Figure 1 of the drawing; the serration on the opposite side of the tongue being restricted to a notch with an inclined surface *f* cooperating with a wedge member *g* bearing

against an abutment on tongue floor *h*. 55

The serration of the tongue on the side adjacent rail member *b* showing likewise inclined surfaces such as *c* acting on tightening of the nuts on bolts *d* to shift the tongue towards the branch track rail *e* so that the end of the tongue is brought into intimate contact with the end of the rail. The arrangement of the inclined surfaces *e* and *f* on opposite sides of the tongue secures symmetry of shifting tendencies with relation to the longitudinal axis of the tongue; however if desired the provision of inclined shifting surfaces may be restricted to one side of the tongue only. 60 65

In order to firmly position the tongue on its floor *h* and to avoid any displacement during lateral adjustment of the tongue the tongue should be strongly pressed down on its floor. To this end the foot portion of the tongue is provided with an incline *i* and the floor with an incline *k*, a clamp *l* being put on such inclines and brought into firm engagement therewith by fastening bolt *d*. The same effect on the opposite side of the tongue is secured by an incline *m* on supplemental rail *b* or by the inclined under side *n* of the head of supplemental rail *b*. 70 75 80

It appears from the foregoing description that a firm connection of the tongue root with the body part or skeleton is secured 85 whereby the bottom surface of the tongue root is tightly pressed against the floor member of the structure. At the same time the construction allows easy removal of the tongue for repair which can be effected after removal of cover plate *o* by loosening of the nuts of bolts *d*, whereafter the tongue can be laterally displaced so that it becomes free from engagement with supplemental rail *b* and can be lifted from its cage. 90 95

The embodiment illustrated in Figures 6-8 is distinguished from that of Figures 1-5 mainly thereby that the serration of the tongue root, whereby a firm connection of the tongue with the body part or skeleton of the structure is secured, is not provided at a lateral surface of the tongue root but at the bottom surface, this being in some respects a more convenient manner. In this case the serrations of the bottom surface of the tongue and of the top surface of the floor member *h* consist in the provision of a groove in each of them. A wedge member 100 105

q is inserted into said grooves and tightened therein by a bolt *d* with a nut thereon. By providing one of the grooves receiving the locking wedge *q*, with a suitably inclined edge a shifting effect can be exercised on the tongue by tightening the wedge *q*. As illustrated on the drawing the groove in the bottom surface of the tongue is provided with, an inclined edge *p* which is in contact with one lateral edge of wedge *q* whereas the edge *r* of the groove in the floor member *h* with which the other lateral edge of the wedge *q* contacts is perpendicular to the longitudinal axis of the tongue. The tightening of wedge *q* brings the end of the tongue in the same way into intimate contact with the adjacent end of the branch track rail *e* as the tightening of the nuts of bolts *d* in the embodiment of Figures 1-5 by the inclined surfaces *c* and *f*. The tongue is pressed down on floor *h* by clamp *l*, as appears from Figure 3 which as above mentioned illustrates not only the section III-III of Figure 1 but also that of Figure 6.

Also in the embodiment of Figures 6-8 the tongue can easily be removed without opening the pavement.

The reliable operation depends from sufficient resiliency of the tongue irrespective its strength and from the firmness of the connection of the branch track rail *e* with the switch structure.

High resiliency of the tongue combined with high strength can be secured by providing the tongue on both its sides with grooves *t*; *u* as illustrated in Figures 9 and 10 the grooves preferably extending substantially from the tongue root, which is firmly connected with the switch structure, to the point of the tongue.

The firm connection of the branch track rail *e* with the switch structure is secured, as illustrated, by bolts *s* connecting rail *e* with supplemental rail *b* and can further be improved, if desired, by bolting or welding rail *e* to the common base plate of the switch structure.

What we claim is:

1. In a tramway switch construction a switch body or skeleton and a resilient switch tongue connected therewith, the interconnected elements provided each with a serration and the serrated parts being firmly locked together.

2. In a tramway switch construction a switch body or skeleton and a resilient

switch tongue connected therewith, the interconnected elements provided each with a serration at least one serration comprising a surface which is inclined to the longitudinal axis of the tongue, the serrated parts being firmly locked together, the inclined surface of a serration being in engagement with a member adapted to be moved transversely to the longitudinal axis of the tongue.

3. In a tramway switch construction a switch body or skeleton and a resilient switch tongue, the switch body comprising a floor portion forming a support for the tongue and provided at its upper side with a groove transversely to the longitudinal axis of the tongue, the tongue on its bottom side likewise provided with a transverse groove, and a wedge member inserted in said grooves and firmly connecting the parts together.

4. In a tramway switch construction a switch body or skeleton and a resilient switch tongue, the switch body comprising a floor portion forming a support for the tongue, and provided at its upper side with a groove transversely to the longitudinal axis of the tongue, the tongue on its bottom side likewise provided with a transverse groove, and a wedge member inserted in said grooves and firmly connecting the parts together, the engaging lateral edges of the grooves and of the wedge comprising an edge which is inclined to the longitudinal axis of the tongue and adapted to produce longitudinal shifting of the tongue with relation to the floor in longitudinal direction on displacement of the wedge transversely to the tongue.

5. In a tramway switch construction a switch body or skeleton and a resilient switch tongue, the switch body comprising a floor portion forming a support for the tongue and a supplemental rail connected to the end of the branch track rail and bolted together with the root of the tongue, the supplemental rail and the root of the tongue being provided with contacting inclined surfaces adapted to produce a tendency to press the tongue down on the floor portion on tightening of the nuts on the connecting bolts.

In testimony whereof, we affix our signatures.

PAUL HEIDTKAMP:
PETER MÜLLER.
